(57) **CLAIM**

The ornamental design for a fork lift truck, as shown and described.

DESCRIPTION

FIG. 1 is a perspective view of a fork lift truck taken from the left front showing my new design with the fork extended in a first position;

FIG. 2 is a perspective view thereof taken from the right rear;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view thereof taken from the left front with the fork retracted in a second position;

FIG. 10 is a perspective view thereof taken from the left rear;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.
